UNITED STATES PATENT OFFICE.

ROBERT C. EDWARDS, OF NEW YORK, N. Y., ASSIGNOR TO FEDERAL TELEGRAPH COMPANY, OF SAN FRANCISCO, CALIFORNIA, A CORPORATION OF CALIFORNIA.

DESIGN FOR A RADIOCABINET.

Application filed August 24, 1925. Serial No. 14,574. Term of patent 3½ years.

To all whom it may concern:

Be it known that I, ROBERT C. EDWARDS, a citizen of the United States, and a resident of the city of New York, county of New York, and State of New York, have invented a new, original, and ornamental Design for a Radiocabinet, of which the following is a specification, reference being had to the accompanying drawing, forming part thereof.

The drawing is a perspective view of a radiocabinet, illustrating my new design.

I claim:

The ornamental design for a radiocabinet substantially as shown.

ROBERT C. EDWARDS.
